GLORY HOLE FURNACE

Filed Dec. 20, 1928

UNITED STATES PATENT OFFICE

MELVIN ELIAS MC SWAIN, OF FORT SMITH, ARKANSAS

GLORY-HOLE FURNACE

Application filed December 20, 1928. Serial No. 327,293.

This invention relates to glass furnaces and particularly to what are known as "glory holes," that is, holes through the wall of the furnace through which glass blower tubes are 5 to be inserted for the purpose of heating glass for blowing or for the purpose of finishing glass articles. In finishing glass articles through the ordinary finishing hole in the wall of the "glory hole," the extremity of 10 the article, as for instance a glass chimney, is inserted in the finishing hole in the furnace to soften it. This chimney is supported on a rotatable "snap" or clamp. In the ordinary furnace or "glory hole," the hot gases projected from the finishing hole are projected 15 outward horizontally and, therefore, are projected against or strike the bulbous portion of the chimney. This tends to soften this portion of the chimney and the resilient jaws 20 of the "snap" tend to deform and bend in this softened portion of the chimney.

The general object of the present invention is to avoid this by so forming the finishing hole that the hot gases or blast are directed 25 upward and outward instead of directly in a horizontal plane so that the flame does not strike the bulbous portion of the chimney but only the tip thereof, thus preventing the softening of the article and its consequent 30 deformation by the resilient grip of the handling jack or clamp.

A further object of the invention is to provide a "glory hole" or glass heating furnace having in the furnace wall a series of 35 blower holes or flame holes, these holes being disposed above the finishing holes a distance about two and one-half inches and on the opposite wall therefrom so that the flame will come directly out of the flame hole or 40 blower hole laterally but the lower portion of the flame will strike upward instead of outward and will be diverted to an upward and outward direction by the peculiar formation of the fire brick through which the 45 finishing hole is formed.

A further object is to provide a "glory hole" or glass furnace of the character described which has one straight wall and a curved wall, the straight wall being formed with a 50 plurality of finishing holes and the curved

wall with a plurality of flame or blower holes. The blower holes are disposed in a plane above the finishing holes. By placing the finishing holes in a flat wall, it is possible to use a plurality of jacks mounted upon a carriage, 55 place a plurality of articles to be finished within the resilient clamps of the jacks and force all these articles into the finishing holes at the same time and by curving the opposite wall, provision is made for a plurality of 60 workmen to use these blower holes without interfering with each other which would not be possible were the blower holes disposed in a flat wall.

In the drawings:—
Figure 1 is a side elevation of a "glory hole" constructed in accordance with my invention;

Figure 2 is a vertical sectional view thereof on the line 2—2 of Figure 1;

Figure 3 is a horizontal sectional view thereof on the line 3—3 of Figure 2.

My invention is illustrated in the accompanying drawings wherein 10 designates generally and without detail a furnace constructed in accordance with my invention. This furnace or "glory hole" has a curved wall shown as approximating a semi-circle and designated 11 and a straight wall 12 constituting the chord of the arc. The furnace 80 is heated by a gas blast pipe 13 of any suitable or usual construction extending upward through the bottom of the furnace at approximately the middle thereof. This furnace is formed of fire brick in the usual manner or 85 may be formed in any suitable or desired way but preferably a series of blocks 14 form part of the straight furnace wall 12 through which blocks pass the finishing holes 15. In the ordinary furnace of this character, these finishing holes are disposed with their axes in a horizontal plane. As a consequence, as before stated, the blast of ignited gas is forced 90 out in a horizontal plane and the chimney A or other article which is supported upon the 95 snap or handling tongs B has its body or bulbous portion subjected to these flames.

This tends to soften this bulbous portion and the resilience of the clamp tends to cause its deformation. Many chimneys are thrown 100

away on account of this deformation and many chimneys are counted as seconds on account of this deformation. Instead of being horizontal, the opening 15 which is approximately circular in shape extends upward and outward at an angle of approximately 45° and to this end the upper wall of the hole on the outside face is cut upward and outward while the lower wall of the hole on the inside face of the block or brick 14 is cut downward and inward so that the inner end of the hole flares downward while the upper end of the hole flares upward. The article A is presented to this finishing hole in a horizontal plane and the end which is to be softened or annealed or have its edges rounded by heat is inserted into this hole. The flames of the blast are deflected upward and outward by the peculiar shape of the hole and thus none of the flame comes against the bulbous portion of the glass as heretofore stated. This is a very important feature. The finishing holes are of the ordinary shape, that is, they are approximately circular. These holes are designated 16 and are disposed in the curved wall 11 of the furnace and in a plane above the plane of the finishing holes. These holes 16 have their axes disposed in a horizontal plane and in outward divergent relation to each other, thus enabling a number of workmen to all work conveniently at the same furnace which would not be the case were the wall straight. The ordinary "glory hole" furnace is cylindrical in form with no flat wall. By providing a flat wall, I provide for one-half of the furnace being used for finishing articles and finishing machine while the other half of the furnace is used by the blowers.

With this construction as before stated, the flame as it rises through the furnace will spread out and be deflected laterally and will come out of the blower holes 16 laterally, that is, in an approximately horizontal plane, but the lower portion of the flame will be deflected upward and outward by the peculiar formation of the block through which the finishing hole is made.

Obviously I do not wish to be limited to the exact shape shown in Figure 3 nor to the exact construction of the blocks or members through which the finishing holes are formed as these might be modified in many ways without departing from the spirit of the invention as defined in the appended claims.

It will be seen that I have provided a "glory hole" so constructed that articles such as chimneys may be made by the glass blowers operating the blow device and glass at the blower holes and that these same chimneys may be immediately finished at the finishing holes with finishing machine. Heretofore, the finishing machines were used after the chimneys were cold and had been carried from the blowing room to a "glory hole" used for finishing machines only. In my construction,

one "glory hole" takes care of blowers and the finishing machines at the same time and as fast as the chimneys are made, enabling one finishing boy to finish or crimp the lamp chimneys made by two blowers and eliminating 70 one finisher.

This "glory" hole as heretofore described is the only "glory" hole so designed that it may be used simultaneously by the blowers and by finishing machines.

I claim:—

1. In a glass furnace of the character described, a wall having a finishing hole, the hole having its upper and outer end upwardly and outwardly flared while its inner end is 80 downwardly and inwardly flared.

2. In a glass furnace, a wall having a finishing hole therethrough, the axis of the finishing hole extending approximately upward and outward, the outer end of the finishing hole being ovoid in shape with the small end of the ovoid upward, the inner end of the finishing hole being ovoid in shape with the small end of the ovoid downward.

3. In a "glory hole" furnace having an 90 outer wall, the wall being provided with a series of finishing holes, the series being disposed in a horizontal plane and each finishing hole having its axis extending approximately upward and outward and the wall of the furnace being formed with a series of blower holes, the axes of which are disposed in horizontal planes, the blower holes being disposed above the finishing holes.

4. A "glory hole" furnace having an arcuate wall and a straight chordal wall, the chordal wall being provided with a plurality of finishing holes, the arcuate wall having a plurality of blower holes disposed above the finishing holes.

5. A "glory hole" furnace having an arcuate wall and a straight chordal wall, the chordal wall being provided with a plurality of finishing holes, the chordal wall having a plurality of blower holes disposed above the finishing holes, the finishing holes having their axes inclined upward and outward, the blower holes having a horizontal axis, the axes of the blower holes being disposed in divergent relation to each other.

6. A glass furnace having a vertical wall formed with a finishing hole, the upper wall of the hole extending generally upward and outward with reference to the plane of said wall from the inner face of the wall to the outer face thereof.

7. A glass furnace having a vertical wall formed with a finishing hole, the upper and lower walls of the hole extending generally upward and outward with reference to the 125 plane of said wall from the inner face of the wall to the outer face thereof.

In testimony whereof I hereunto affix my signature.

MELVIN ELIAS McSWAIN.
